United States Patent Office

Des. 175,491
Patented Sept. 6, 1955

175,491

PLATE OR SIMILAR ARTICLE

A. Baker Barnhart, New York, N. Y.

Application February 28, 1955, Serial No. 34,768

Term of patent 7 years

(Cl. D44—15)

The figure is a plan view of a plate or similar article of conventional configuration, showing my new design.

I claim:

The ornamental design for a plate or similar article, as shown and described.
